MARVIN L. CHAPPELL, OF LOS ANGELES, CALIFORNIA, ASSIGNOR TO STANDARD OIL COMPANY OF CALIFORNIA, OF SAN FRANCISCO, CALIFORNIA, A CORPORATION OF DELAWARE

METHOD OF PRODUCING MOTOR FUEL OR GASOLINE FROM PETROLEUM OIL

Application filed January 22, 1927. Serial No. 162,705.

This invention relates to a method for producing gasoline or motor fuel from petroleum oil, and refers particularly to a sequence of operations which will permit a maximum yield of motor fuel or gasoline from crude petroleum oil with a minimum treatment with metallic halides.

Heretofore metallic halides, such as aluminum chloride, ferric chloride, and the like, have been employed in the anhydrous state for producing gasoline or motor fuel from hydrocarbon oils which will not yield distillates of suitable boiling points for use as gasoline or motor fuel. Gasoline or motor fuel has also been derived from crude petroleum oil through straight distillation, the gasoline thus derived being usually referred to as the natural gasoline contained in the crude oil.

Gasoline or motor fuel is generally required to conform to certain specifications as to its boiling point, for instance, those outlined in the Bureau of Mines Bulletin No. 323-A. Such specifications require that 20 per cent. of the gasoline stock shall have boiling points not over 221° F.; that 50 per cent. of the gasoline stock shall have boiling points not over 284° F.; and that 90 per cent. of the gasoline stock shall have boiling points not over 392° F., and that the end boiling point of the gasoline stock shall not be over 437° F. These specifications materially reduce the amount of so-called natural gasoline that can be derived from the crude oil. Accordingly, the usual topping operation separates from the crude oil only a portion of the stock having boiling points within the gasoline or motor fuel range and there remains in the stock after treatment, a considerable percentage of oils having boiling points ranging from approximately 290° F. to 437° F. which cannot be utilized for motor fuel due to lack of lighter ends and accordingly are customarily utilized as kerosene stocks.

Those hydrocarbons having boiling points between 131° F. and 284° F. may be designated as fractions having boiling points within the lower gasoline range, while those hydrocarbons having boiling points between

284° F. and 437° F. may be designated as fractions having boiling points within the upper gasoline range.

The object of the present invention is to provide a method of producing gasoline from crude oil in which substantially all of the natural gasoline stock, including the before-mentioned heavy ends of the gasoline stock, may be separated from the stock and used in the production of gasoline conforming to the required specifications.

Another object of the present invention is to provide a process adapted for producing the deficient light stock required for such gasoline by a reaction between a metallic halide, such as aluminum chloride, and a fraction or cut of petroleum oil best adapted for the production of such stock.

Another object of the present invention is to provide a process for treating petroleum oils which will operate to produce an exceptionally high percentage of low boiling point oils or oils within the lower boiling point range of gasoline stock.

In accordance with the process of the present invention, crude petroleum oil is first distilled or topped to remove all of the natural gasoline or motor fuel stock that will conform to gasoline or motor fuel specifications. At the same time, a reflux distillate from such topping operations such, for example, as includes the kerosene cut of the petroleum oil and preferably also part of the gas oil cut of the petroleum oil, is passed to a vaporizing chamber wherein the portion of such cut having boiling points corresponding to the heavier gasoline or motor fuel stocks are fractionated therefrom and admixed with the gasoline stock from the topping operation. At this period of operation, the resultant gasoline or motor fuel stock will not properly conform to the required specifications. In order to correct such gasoline, the reflux stock from the second vaporizing operation is treated with aluminum chloride or other metallic halide under regulated conditions of temperature, pressure, and quantities of reagents employed so as to produce a gasoline or motor fuel stock having an excess of high boiling point oils or oils com-

ing within the upper portion of the gasoline boiling point range, these stocks then being added or admixed with the natural gasoline stock. In this way, the process results in the production of a very large amount of gasoline or motor fuel of the required specifications from a crude oil while at the same time, there is a minimum conversion of high boiling point oils to low boiling point oils required.

Various further features of the present invention will be understood from a description of a preferred form or example of a process embodying the invention. For this purpose, reference is made to the accompanying drawing in which there is diagrammatically illustrated an apparatus suitable for conducting the preferred process.

The drawing represents the apparatus diagrammatically and mainly in elevation and vertical section.

Referring to the drawing, 2 indicates an initial vaporizing chamber or topping still which is preferably mounted over a furnace 3 provided with the burner 4 or other suitable means by which said still may be heated. The still 2 is provided with a residual draw-off line 5 and also with a crude oil inlet line 6.

30 The still 2 is provided with the vapor dome 7 connected with the vapor line 8 leading to a dephlegmator or reflux tower 9. Preferably in the upper portion of said dephlegmator are provided lines 10 through which the crude oil in line 6 passes, thereby providing a control over the discharge temperature of the vapors from the dephlegmator and also pre-heating the crude oil in the still 2. It is understood that the dephlegmator 9 may be of any usual or preferred construction of tower adapted for fractionally separating petroleum vapors. The dephlegmator 9 is provided with a vapor line 11 which leads to a condenser 12 and hence to a tank 13 for receiving the produced gasoline or motor fuel.

45 The reflux tower 9 is provided with a line 14 by which the oils condensed therein may be withdrawn and passed to a still or vaporizing chamber 15. The still 15 is provided with suitable heating means, such as the furnace 16 having the burner 17. The still 15 has a vapor dome 18 connected with the vapor line 19 leading to a dephlegmator or reflux tower 20. Said dephlegmator 20 is also preferably provided with lines 21 through which the crude oil in line 6 passes for conserving the heat of the vapors and for lowering the discharge temperature thereof. The vapors pass from dephlegmator 20 to line 22 which is preferably connected with the vapor line 11.

50 The lower end of the dephlegmator 20 is connected by a line 23 having a valve 24 to a pump 25, the outlet end of which is connected by the line 26 with a reaction cham-

ber 27. There is also preferably provided a cross-over line 28 having the valve 29 between the still 15 and the line 23. The reaction chamber 27 may be of any suitable construction adapted for contacting metallic halide and petroleum oil, preferably being designed for operation under high pressures. The reaction chamber 27 is indicated as provided with a shaft 30 mounting a plurality of scrapers and agitator members 31 by which the contents of the still may be agitated and the sides maintained free of coke or sludge. The reaction chamber 27 is preferably mounted over a furnace 32 having the burner 33 or other suitable means by which the contents of the reaction chamber 27 may be heated. 34 indicates a feeding device for introducing metallic halide into the reaction chamber and 35 indicates a vapor line leading from the reaction chamber to the dephlegmator 20. Said vapor line is indicated as including a pressure dam or regulating valve 36. There is also provided a line 37 having a valve 38 leading from the storage tank 13 to the inlet end of pump 25 by which a portion of the gasoline stock may, if desired, be passed into reaction chamber 27 for purposes hereafter explained.

55 The preferred process as carried out in the apparatus described, is as follows: Crude petroleum oil is continuously passed through line 6 into vaporizing chamber or still 2. Within said vaporizing chamber or still 2, the crude oil is heated to a temperature sufficient to vaporize therefrom all of the motor fuel or gasoline stock. The still temperature required normally is around 550° to 650° F. Within the still 2 all of the gasoline or motor fuel stock is vaporized together with kerosene and part of the gas oil stock of the crude. 100 The residual crude is continuously withdrawn from line 5.

60 The vapors evolved in still 2 pass through line 8 into dephlegmator 9 wherein said vapors are subjected to fractionation to separate therefrom all of the stock which will produce a motor fuel of correct specifications. For example, the temperature of the vapors discharged from dephlegmator 9 is usually maintained around 300° F., and the gasoline 115 or motor fuel stock separated conforms to the following specifications: 20 per cent. of said stock has boiling points not over 221° F., 50 per cent. not over 284° F., 90 per cent. not over 392° F., end point not over 437° F. 120

65 A reflux distillate having a boiling point range of for example, between 290° and 630° F. is continuously conducted from the reflux tower line 14 into still 15. Said reflux distillate condenses a considerable quantity of stock having boiling points lying in the upper motor fuel or gasoline range and the stock also includes the kerosene and some gas oil fractions. Within the still 15, said stock is continuously subjected to vaporiza- 130

tion utilizing in part its residual heat at a temperature sufficient to at least vaporize from said oil all of the stock having boiling points within the gasoline range or, for example, all stock having boiling points lower than approximately 437° F.

The vapors from still 15 are passed through line 19 into dephlegmator 20 wherein all the oil having boiling points within the gasoline stock is separated and the remaining oils condensed and collected. The gasoline stock derived from this operation continually passes off and intermingles with the gasoline stock from dephlegmator 9 and the two stocks are condensed in condenser 12. Were such two operations the only source of materials flowing into the gasoline tank 13, the resultant stock therein would not conform to gasoline or motor fuel specifications because of a lack of proper low boiling point stock. In order to correct said boiling point range, the reflux stock from dephlegmator 20 with or without a withdrawal of part of the unvaporized oil from still 15 is passed through pump 25 and hence into reaction chamber 27 for reaction with metallic halide for the production of such high boiling point stock. Within reaction chamber 27, said oils continuously come into contact with metallic halide supplied from the charger 34 under regulated conditions to produce a low boiling point naphtha, adapted to provide the low boiling point constituents in which the stock in tank 13 is deficient.

The amount of aluminum chloride used in reaction chamber 27 may be varied, depending upon the petroleum oil treated and the products desired. In practice, I prefer to use from $\frac{1}{4}$ of a pound to as high as $1\frac{1}{2}$ pounds of anhydrous aluminum chloride per gallon of oil charged.

In order to cause the metallic halide and hydrocarbon oil reaction in chamber 27 to produce this character of stock, the reaction is preferably conducted under high pressure such as, for example, 50 pounds gage or higher, and the temperature is preferably around 500° to 700° F. Generally the higher the temperature and pressure, the lower will be the boiling point of the stock produced. The quantity of low boiling point stock can also be increased by the addition of larger amounts of metallic halide.

The residual metallic halide sludge is preferably continuously withdrawn from line 40 while the vapors of produced low boiling point stock are passed through line 35 and pressure regulating valve 36, and hence through dephlegmator 20 to condenser 12, finally entering the gasoline or motor fuel receiver 13 wherein the three sources of supply from said tank are blended to form a motor fuel of the required specifications.

At times, a certain quantity of gasoline or motor fuel may be passed from the receiver

13 to the reaction chamber 27 if sufficient low boiling point stock cannot otherwise be obtained. The addition of materials from tank 13 decreases the boiling point of the products from reaction chamber 27 inasmuch as the lighter the hydrocarbon fed into reaction chamber 27 the lower the boiling point of the products of the reaction will be.

As a result of the process of the present invention all of the constituents of crude oil lying within the boiling point range of gasoline or motor fuel may be utilized for this purpose with the minimum artificial production of motor fuel for correction of the boiling point range of the product.

It is to be understood that the still 15 and the dephlegmator 20 may be omitted from this operating process without departing from the spirit of the invention. In this case, the evolved vapors coming from the reaction chamber 27 would be conducted directly to dephlegmator 9 and there commingled and blended with the vapors from the still 2 and the refluxed oil would be conducted directly through line 14 which would be connected to the suction side of pump 25. In this case, it will be necessary to use a dephlegmator of such construction as to permit the separation of all stock within the gasoline boiling range.

While the process herein described is well adapted for carrying out the objects of the present invention, various modifications and changes may be made without departing from the invention and the invention includes all such modifications and changes as come within the scope of the appended claims.

I claim:

1. A process of producing blended motor fuel comprising first distilling from crude petroleum oil the lower boiling point fractions including gasoline stocks boiling below 437° F. and higher boiling point oil, subjecting the vapors to reflux separation in which operation an overhead gasoline stock vapor is formed containing oils substantially all of which have boiling points below 437° F., while forming a reflux condensate of higher boiling point oils, re-distilling from said reflux condensate a gasoline stock having boiling points between 284° F. and 437° F., subjecting the remaining higher boiling point oil after the separation of such last mentioned vapors to reaction with metallic halide under suitable temperature and pressure to decompose the oil and form a gasoline stock having boiling points mainly below 284° F., and blending the three gasoline stocks thus produced.

2. A process of producing a blended motor fuel in which 20% of the fuel has boiling points not over 221° F., 50% of the fuel has boiling points not over 284° F., 90% of the fuel has boiling points not over 392° F., and

the end point of the fuel is not over 437° F. which comprises, subjecting crude oil to distillation while subjecting the evolved vapors to reflux action, in said refluxing action forming as vapors a gasoline stock the boiling points of which are below 437° F., and a reflux condensate stock containing oils boiling between 284° F. and 437° F. along with higher boiling point oils, subjecting the reflux condensate to re-vaporization to vaporize therefrom oils having boiling points between 284° F. and 437° F., subjecting the remainder of the reflux condensate to reaction with metallic halide under conditions of temperature and pressure to decompose the same and produce sufficient fractions having boiling points below 284° F. to produce a motor fuel stock when blended with the aforesaid oils boiling between 284° and 437° F. to form a motor fuel of the above specifications, and mixing the three motor fuel stocks thus produced in such manner as to form a motor fuel of the aforesaid specifications.

3. A process of producing blended gasoline conforming with the specifications that not over 20% of the gasoline shall have boiling points over 221° F. and not over 50% of the gasoline shall have boiling points over 284° F., and not over 90% of the gasoline shall have boiling points over 392° F. and that the end point of the gasoline shall not be over 437° F. which comprises, first distilling crude oil while subjecting the evolved vapors to a reflux action, in said reflux action evolving as vapors oils boiling below 437° F. while forming a condensate which includes, along with heavier oils, oils boiling between 284° and 437° F., vaporizing from the condensed oils those fractions having boiling points between 284° and 437° F., subjecting the remaining condensed oils to reaction with metallic halide under temperature and pressure conditions sufficient to decompose the oils to form mainly low boiling point oils containing sufficient fractions having boiling points within the range of 437° F. and 284° F., so that these low boiling point oils when blended with the oils have boiling points between 284° and 437° F. and the oils produced with vapors from the first refluxing operation will form a gasoline of the aforesaid specifications, and blending the three stocks thus produced together.

4. A process of producing blended motor fuel which conforms to the specifications that 20% of the fuel shall have boiling points not over 221° F., 50% shall have boiling points not over 284° F., 90% shall have boiling points not over 392° F. and that the end boiling point shall not be over 437° F. which comprises, first distilling and removing from crude petroleum oil a vapor the boiling points of which correspond to the above specifications, while simultaneously forming a reflux condensate, vaporizing from said reflux condensate oils hav-

ing boiling points between 284° F. and 437° F., subjecting the remainder of the reflux condensate to decomposing action with metallic halide under suitable temperature and pressure conditions to form low boiling point oils boiling mainly below 284° F., and blending the oils produced from said first distillation with the oils boiling between 284° and 437° F. and with the oils produced from said metallic halide reaction boiling mainly below 284° F. so as to produce a motor fuel which conforms with the above set forth specifications.

5. A process of producing a blended motor fuel which comprises vaporizing from crude petroleum oil the gasoline boiling point fraction together with higher boiling point fractions, subjecting the vapors to a reflux separation wherein the gasoline boiling point fraction is left as an overhead vapor while the remaining higher boiling point fractions are condensed, re-vaporizing the condensed oil to separate therefrom those fractions having relatively high boiling points within the gasoline range and a further overhead vapor, subjecting the oil remaining after the separation of such last mentioned fractions to reaction with metallic halide under suitable temperature and pressure to decompose the oil and form fractions having relatively lower boiling points within the gasoline range, and blending the vapors so produced so that the entire overhead of the crude forms specification gasoline.

6. A process of producing blended motor fuel which comprises topping the crude oil while separating from the vapors a gasoline boiling point fraction as vapor and a kerosene fraction as a condensate, vaporizing the kerosene fraction to separate therefrom those fractions having relatively high boiling points within the gasoline range, subjecting the remaining kerosene fraction to reaction with metallic halide under conditions of temperature and pressure to decompose the same and produce sufficient fractions having relatively low boiling points within the gasoline range to produce specification gasoline when blended with the fractions having relatively high boiling points within the gasoline range which were vaporized from said kerosene fraction, and mixing all of the gasoline fractions so produced to form a specification gasoline.

7. A process of producing a blended gasoline which comprises first passing crude oil containing gasoline through a continuous topping operation wherein both gasoline and kerosene fractions are vaporized, subjecting the vapors to reflux separation, thereby separating from said vapors those fractions which will form a specification gasoline, and condensing the remaining vapors including those having boiling points between 284° and 437° F. but which are unsuited for specifica-

tion gasoline because of the presence of insufficient vapors having boiling points between 137° and 284° F., vaporizing from the condensed oil those fractions having boiling points between 284° and 437° F., subjecting the remaining oil to reaction with metallic halide under temperature and pressure conditions sufficient to decompose the oil to form lower boiling point oil containing sufficient fractions having boiling points between 137° and 284° F., so that the lower boiling point oil from said decomposing reaction may be blended with the higher boiling point fractions within the gasoline range to produce a specification gasoline, and blending the three gasoline fractions thus produced.

8. A process of producing blended motor fuel comprising first topping and removing from crude petroleum oil which contains gasoline those fractions which conform to the specifications of a gasoline stock, vaporizing from said crude oil a heavier distillate, including fractions having relatively high boiling points within the gasoline range, separating such latter fractions from said heavier oil, subjecting the remainder of said heavier oil fractions to decomposing reaction with metallic halide under suitable temperature and pressure to form low boiling point fractions containing sufficient excess of fractions having relatively lower boiling points within the gasoline range so that said lower-boiling point oils, when blended with said fractions having relatively higher boiling points within the gasoline range, will form a blended product conforming to specifications for gasoline stock, and so blending said fractions that thereby substantially the entire overhead from the topping operation produces specification gasoline.

Signed at Los Angeles, Calif., this 5 day of January, 1927.

MARVIN L. CHAPPELL.
